R. F. CAMPBELL

PENDANT FOR WATCHCASES

Filed July 13, 1923

INVENTOR
ROBERT F CAMPBELL

BY

Edgar D. Smith
ATTORNEYS

UNITED STATES PATENT OFFICE.

ROBERT F. CAMPBELL, OF BROOKLYN, NEW YORK.

PENDANT FOR WATCHCASES.

Application filed July 13, 1923. Serial No. 651,213.

To all whom it may concern:

Be it known that I, ROBERT F. CAMPBELL, a citizen of the United States, and residing at Brooklyn, in the county of Kings, and 5 State of New York, have invented certain new and useful Improvements in Pendants for Watchcases, of which the following is a specification, such as will enable those skilled in the art to which it appertains to 10 make and use the same.

This invention relates to pendants for watch cases or the frames in which the movements are mounted and particularly to the structure of such pendants and the 15 method of attaching the same to the watch case and the formation of the watch stem aperture in said pendant and case; and the object of the invention is to provide a pendant of the class specified which is of simple construction and which may be readily mounted 20 in connection with a watch case and secured thereto to produce a strong and durable pendant as well as to reinforcing that portion of the case through which the stem of 25 the watch passes; a further object being to provide a construction of the class and for the purpose specified which is adapted for use principally in comparatively thin watch cases and in which the case is usually weakened 30 in the formation of the aperture therein, through which the stem passes.

The invention is fully disclosed in the following specification, of which the accompanying drawing forms a part, in which the 35 separate parts of my improvement are designated by suitable reference characters in each of the views, and in which:

Fig. 1 is a side view of a watch case showing my improved pendant mounted in connection therewith.

Fig. 2 is a diagrammatic view showing a part of a watch case and the pendant spaced apart and illustrating the first step in attaching the pendant to the case.

Fig. 3 is a view similar to Fig. 2 but showing the pendant mounted on the case.

Fig. 4 is a section on the line 4—4 of Fig. 3 showing the formation of the stem aperture in the case.

Fig. 5 is a section on the line 5—5 of Fig. 4; and,

Fig. 6 is a bottom plan view of the pendant on an enlarged scale.

In Fig. 1 of the drawing I have shown at 55 10 a watch case of predetermined construction, for illustrating one use of my inven-

tion and this case is provided at the periphery thereof with an annular projecting body 11 which is of less dimensions than the transverse dimensions of the case as a whole, 60 as clearly shown in Fig. 4 of the drawing, and at 12 I have shown my improved pendant. In Fig. 1, I have shown at 13 a stem passed through the pendant and watch case but the movement of the watch is omitted. 65

The pendant 12 comprises a body portion 14 having a downwardly directed oblong and flared extension 15, the lower face of which is preferably curved as shown at 16 to correspond with the curvature of the projecting portion 11 of the casing 10. The pendant 12 is provided centrally thereof with a vertical bore 17, enlarged at its upper end as shown at 18, and the enlargement of the bore extends into a sleeve portion 19 70 at the top of the pendant and the lower face 16 of the pendant is provided at the opposite sides of the bore 17 and in line therewith with two downwardly projecting members 20 forming a U-shaped or yoke-shaped projection, and the outer faces of the members 20 are preferably rounded as shown at 21 in Fig. 6 of the drawing.

The projections 20 on the pendant may be formed in many ways; for example, a projecting stud may be formed on the pendant as a whole and this stud milled out to form the separate members 20, or the pendant may have a projecting tubular stud or sleeve which will be milled to form the separate 90 members 20 or the entire pendant may be molded or cast into the form shown and with the bores 17 and 18 therein, or these bores may be drilled after the body of the pendant as a whole has been formed. 95

In mounting the pendant 12 upon a watch case, after said pendant has been formed in the manner above described, the same is placed on a predetermined point of the case with the members 20 spanning the projecting portion 11 of the case as clearly shown in Fig. 4 of the drawing, and the pendant is secured to the case by soldering, brazing or any other desired manner, but preferably by soldering the curved face 16 of the pendant to the periphery of the projection 11 to attach the pendant to the case as shown in Fig. 3 of the drawing. Assuming that the bores 17 and 18 have been formed in the pendant the next step in building the pendant construction of the case will be to insert a drill of the size of the bore 17 into 100 105 110

said bore and drill a hole 22 in the casing 10 and through the projection 11 thereof as clearly shown in Figs. 4 and 5 of the drawing. The pendant and case are now in condition to receive the usual watch stem, and it will be noted that that portion of the case 10 or the projection 11 thereof in which the aperture 22 is formed will be reinforced by the members 20 of the pendant which are 10 located at the opposite sides of the projection 11 of the case 10 where the aperture 22 is located.

My improved construction, as will be apparent, materially simplified the mounting 15 of a pendant in connection with a watch case as well as to provide a strong and durable construction and particularly with reference to the reinforcement of the case where the pendant is mounted in connection therewith, and while I have shown a specific form 20 of case as well as a specific form of pendant, it will be understood that I am not necessarily limited in this respect, and various changes in and modifications of the construction herein shown and described may 25 be made within the scope of the appended claims without departing from the spirit of my invention or sacrificing its advantages.

Having fully described my invention, 30 what I claim as new and desire to secure by Letters Patent, is:—

1. A pendant for watch cases of the class described comprising a pendant body provided with a U-shaped projection adapted 35 to span and reinforce a predetermined portion of a watch case when the pendant is mounted in connection therewith.

2. A pendant for watch cases of the class described comprising a pendant body provided with a U-shaped projection adapted 40 to span and reinforce a predetermined portion of a watch case when the pendant is mounted in connection therewith, and said pendant being provided with a stem 45 aperture.

3. A pendant for watch cases of the class described comprising a pendant body provided with a U-shaped projection adapted 50 to span and reinforce a predetermined portion of a watch case when the pendant is mounted in connection therewith, said pendant being provided with a stem aperture, and the case with a similar aperture in line with the pendant aperture.

4. The combination with a watch case provided with an annular projecting beaded member of a pendant fashioned to fit snugly upon the beaded member of said case, and said pendant being provided with means 60 overlapping the sides of said beaded member at a predetermined point for reinforcing the case or the beaded member thereof.

5. The combination with a watch case provided with an annular projecting beaded 65 member of a pendant fashioned to fit snugly

upon the beaded member of said case, said pendant being provided with means overlapping the sides of said beaded member at a predetermined point for reinforcing the case or the beaded member thereof, and the 70 case pendant being provided with a stem aperture.

6. The combination with a watch case provided with an annular projecting beaded member of a pendant fashioned to fit snugly 75 upon the beaded member of said case, and said pendant being provided with a yoke-shaped portion adapted to receive said beaded member and to reinforce that portion of the beaded member in connection 80 with which the pendant is mounted.

7. The combination with a watch case provided with an annular projecting beaded member of a pendant fashioned to fit snugly upon the beaded member of said case, and 85 said pendant being provided with a yoke-shaped portion adapted to receive said beaded member and to reinforce that portion of the beaded member in connection with which the pendant is mounted, said 90 yoke-shaped member comprising spaced elements, the outer faces of which are arc-shaped in form.

8. The herein described method of mounting a pendant in connection with a watch 95 case, said case being provided with an annular projecting member which consists in providing a suitable pendant body having a stem aperture therein, and a yoke-shaped projection in line with said aperture, mounting said pendant upon and securing the same to said case or the annular projection thereof with the yoke-shaped projection of the pendant spanning the annular projection of said case. 100

9. The herein described method of mounting a pendant in connection with a watch case, said case being provided with an annular projecting member which consists in providing a suitable pendant body having 110 a stem aperture therein, a yoke-shaped projection in line with said aperture, mounting said pendant upon and securing the same to said case or the annular projection thereof with the yoke-shaped projection of 115 the pendant spanning the annular projection of said case, and then drilling an aperture in said case and in line with the aperture of said pendant body.

10. The herein described method of 120 mounting a pendant in connection with a watch case which consists in providing a pendant body provided with a stem aperture and with spaced projecting elements on the bottom face thereof and in line with 125 said aperture, soldering said pendant body to said case with the spaced projecting elements thereof overlapping predetermined portions of the case.

11. The herein described method of 130

mounting a pendant in connection with a watch case which consists in providing a pendant body provided with a stem aperture and with spaced projecting elements on the bottom face thereof and in line with said aperture, soldering said pendant body to said case with the spaced projecting elements thereof overlapping predetermined portions of the case, and then drilling an aperture in the case in axial alinement with 10 the aperture in the pendant body.

In testimony that I claim the foregoing as my invention I have signed my name this 7th day of July 1923.

ROBERT F. CAMPBELL.
